(57) **CLAIM**

The ornamental design for a building component, as shown and described.

DESCRIPTION

FIG. 1 is a plan view of a building component showing our new design.

FIG. 2 is a perspective view of the building component showing our new design.

FIG. 3 is a left side view of the building component showing our new design.

FIG. 4 is a right side view of the building component showing our new design; and,

FIG. 5 is a rear view of the building component showing our new design.

In FIG. 3, the broken lines indicate an interior portion of the component that forms no part of the claimed design.

1 Claim, 5 Drawing Sheets
